UNITED STATES PATENT OFFICE.

RUDOLPH HOFFMAN, OF KANKAKEE, ILLINOIS, ASSIGNOR TO SEARS, ROEBUCK AND COMPANY, OF CHICAGO, ILLINOIS, A CORPORATION OF NEW YORK.

DESIGN FOR A RANGE.

49,353.

Specification for Design.

Patented July 11, 1916.

Application filed December 20, 1915. Serial No. 67,905. Term of patent 7 years.

To all whom it may concern:

Be it known that I, RUDOLPH HOFFMAN, a citizen of the United States, residing at Kankakee, in the county of Kankakee and State of Illinois, have invented a new, original, and ornamental Design for Ranges, of which the following is a specification, reference being had to the accompanying drawing, forming a part thereof.

The drawing is a perspective view of a range showing my new design.

I claim:

The ornamental design for a range, as shown.

RUDOLPH HOFFMAN.
